UNITED STATES PATENT OFFICE.

FREDERICK W. PENDERGAST, OF WALTHAM, MASSACHUSETTS.

DESIGN FOR A BROOM-HOLDER MEMBER.

SPECIFICATION forming part of Design No. 35,289, dated November 12, 1901.

Application filed September 25, 1901. Serial No. 76,581. Term of patent 7 years.

To all whom it may concern:

Be it known that I, FREDERICK W. PENDERGAST, a citizen of the United States, residing at Waltham, in the county of Middlesex and State of Massachusetts, have invented and produced a new and useful Design for Broom-Holder Members; and I do hereby declare the following to be a full, clear, and exact description of the invention, such as will enable others skilled in the art to which it appertains to make and use the same.

This invention relates to devices for securing broom-heads of broom-corn to handles.

In the drawings, Figure 1 is a front view of one broom-holder member. Fig. 2 is a plan view. Fig. 3 is a sectional side view.

The leading or material features of the design consist of a semicylindrical upper portion A, having a hole a' at its middle part; a horizontal portion B, arranged at a right angle to the axis of the part A and of concavo-convex cross-section throughout its length,

said portion terminating in a single curve b at its top, a reverse curve b' at its bottom, a curve c at the back, and two flat edges c' at 25 the top and bottom of its front portion; a concavo-convex inclined portion C, which connects the lower edge of the upper portion A with the middle portion of the horizontal portion B, and a series of triangular projections or teeth D, which project laterally at 30 intervals from the upper and lower edges of the horizontal portion B.

What I claim is—

The design for a broom-holder member, as 35 herein shown and described.

In testimony whereof I affix my signature in presence of two witnesses.

his
FREDERICK W. X PENDERGAST.
